HARRY F. CUNNING, OF ROANOKE, VIRGINIA

LUBRICATING DEVICE

Application filed October 7, 1929. Serial No. 397,967.

My invention relates to improvements in lubricating devices and more specifically to devices for lubricating the journals of railway cars and the like.

As is well known railway car journals are lubricated by waste thoroughly saturated in oil and the proper lubrication of the journals is entirely dependent upon the contact of the oil waste therewith. Considerable difficulty has heretofore been experienced in maintaining the waste in contact with the journal, due to the fact that the vibration to which the journal boxes are subjected causes the waste to settle and pack, thereby leaving a space between the waste and the journal.

Furthermore, difficulty is often experienced with what is commonly termed "waste grab", that is, portions of the waste get in between the journal and its bearing. This condition is usually brought about by the bearing being lifted from its journal, due to severe shocks caused by emergency application of the car brakes or sudden stops from any cause. These conditions, namely, first, the journal and waste not being in contact and, second, portions of the waste getting in between the bearing and journal cause the bearing to heat inducing what is commonly known as a hot box.

The primary objects of my invention are, therefore, to provide simple and reliable means for holding the waste in contact with the journal and in preventing circumferential movement of the waste.

A primary feature of the invention consists in associating with the journal box a pair of pivotally mounted members, each of which is provided with a plurality of fingers for maintaining the waste in proper contact with the journal.

Another feature of the invention consists in providing the interior surface of the journal box with a plurality of recesses respectively adapted to receive the fingers of the waste cooperating members so that when the latter are in inoperative positions the lower inner surface of the box will be practically free of projections or protuberances to permit the waste to be easily and conveniently inserted into and withdrawn from the box.

Still another feature of the invention consists in combining with the waste cooperating members spring means normally urging the members in a direction so as to maintain the waste in engagement with the journal.

Other and more specific features of the invention residing in advantageous forms, combinations and relations of parts will hereinafter appear and be pointed out in the claims.

In the drawing illustrating a preferred embodiment of the invention;

Figure 1 is a fragmentary longitudinal sectional view of a journal box showing the invention applied thereto, the journal being omitted.

Figure 2 is a fragmentary view partly in elevation and partly in section, the sectional portion of the view being taken in a plane designated by the line 2-2, Figure 1.

Figure 3 is a fragmentary sectional view illustrating the lubricating device in one of its operative positions, the left hand portion of the figure being taken in a plane designated by line 2-2, Figure 1 and the right hand portion by the figure being taken in a plane designated by line 3-3, Figure 1.

Referring more particularly to the drawing 1 indicates the journal box, only the lower half being illustrated as the construction of the upper half of the box, since it forms no part of the invention, may be of any usual or desired construction. The major portion of the lower half of the interior surface of the box is semi-cylindrical in section, the center of curvature thereof being preferably disposed in the same vertical plane as the center of the journal 2. As is usual in journal box construction the rear wall or walls 3 thereof are suitably apertured as at 4 to receive the journal and the opposite wall is formed with an opening 5 normally closed by a lid (not shown).

Pivottally mounted within the box is a pair of members 6, each of which comprises a main rod or shaft 7 and a plurality of spaced arms or fingers 8. The members 6 are respectively disposed on opposite sides of the center of the journal and are preferably mounted adjacent the side walls of the box.

The inner ends of the shafts 7 are respectively journaled in openings 9 formed in the rear wall 3 of the box. Surrounding these apertures the rear wall may advantageously be 5 formed with inwardly projecting bosses 9a and in order to prevent longitudinal movement of the members 6 toward the rear wall 3 the portions of the shafts cooperating with the apertures are preferably reduced to form 10 a shoulder 10.

To support the outer ends of the shafts 7 the side walls of the box may be conveniently integrally formed with inwardly projecting lugs or brackets 11. Each of the brackets is 15 substantially U-shape in cross section and is provided with an end wall 12 to prevent the associated shaft 7 from moving longitudinally in a direction toward the front wall of the box. The shafts 7 may be retained in 20 their respective brackets 11 by any suitable means such as screws 13 respectively adapted to overlie the shafts thereby preventing their unintentional or accidental upward movement.

25 The waste cooperating fingers 8 are preferably formed integral with their shafts 7 and while any number of the fingers may be used it has been found that three will sufficiently and adequately perform their intended function. The fingers are preferably shaped so as to conform to the contour of adjacent portions of the interior of the box and since, as has already been stated, the interior surface of the box adjacent the lower 30 portion is semi-cylindrical the fingers are curved, their center of curvature being coincident with that of the curved inner surface of the box. The interior of the box is formed with a plurality of recesses or depressed portions 14 for receiving and housing the fingers 8 so that when they are in inoperative position their outer surfaces will be flush with adjacent portions of the inner surface of the box. Thus it will be perceived 40 that the lower portion of the inner surface of the box is free from projections and protuberances thereby permitting the ready insertion of waste into the box.

Associated with each of the members 6 is 50 a means for exerting sufficient pressure on the oil waste to maintain it in proper contact with the journal and for preventing displacement of the waste. In the present embodiment of the invention this means consists 55 of a depending arm 15 which may be conveniently formed integral with the associated shaft 7, a spring 16 and mechanism for varying the force exerted by the spring on the arm 15. As the arms 15 are disposed substantially vertically when the members 6 are 60 in inoperative positions the box is formed with cavities or recesses 17 for receiving or housing the arms 15.

65 While the spring 16 and its associated arm 15 may be operatively connected in any de-

sirable manner it is preferred that the arm be provided with a lug or stud 18 which is adapted to be encircled by the coil spring and is formed with an opening or aperture through which the end of the spring is inserted. This manner of connecting the arm and spring eliminates the necessity of employing additional parts or appurtenances. Extending outwardly from the sides of the box adjacent the recess 17 are projections 19 70 which are respectively interiorly threaded to receive exteriorly threaded sleeves 20 which are preferably closed at their outer ends and formed with a head, such as a hexagonal nut-like portion 21 for cooperating with a wrench or the like, which may be employed for rotating the sleeves in the desired direction. The end of the coil spring 16 opposite to the end attached to the arm 15 is disposed within the sleeve 20 and abuts against its closed end. It will thus be perceived that by rotating the sleeves to cause them to move inwardly force is transmitted to the arms 15 through the intermediacy of the coil springs 16 whereby the shafts 7 are rotated in a direction to move the fingers 8 upwardly. Any suitable means such as a lock nut 22 may be employed for maintaining the sleeve 20 in a desired position of adjustment.

The manner of associating and disassociating the members 6 with the journal will, of course, be readily appreciated. When the parts are in the position as indicated in Figure 1 and it is desired to remove them from the box, the members 6 are rotated by hand to withdraw the coiled springs 16 from their sleeves 20. The screws 13 are then withdrawn from the brackets 11 to permit the outer ends of the members 6 to be elevated. After this is accomplished the inner ends of the shafts 7 may be readily withdrawn from the apertures 9 in the inner wall of the box and the members bodily removed from the box through the opening 5. In assembling the members practically the reverse operation is performed, namely, the members 6 with their coiled springs attached, are inserted into the box through the opening 5, the inner ends of the shafts 7 are inserted in the apertures therefor, the outer ends of the shaft 7 are dropped into their supporting brackets 11, the screws 13 properly applied and the coil springs 16 inserted in their sleeves 20.

After the parts have been also assembled the sleeves 20 are so adjusted that the fingers 8 and the arms 15 of the members may fall by gravity into their respective recesses or housings. The waste which has already been saturated with the required amount of oil may then be inserted in the box. Under present approved methods of packing journal boxes enough waste must be used to fill the space between the underside of the journal and the bottom of the box so that the 120 125 130

waste will be held firmly in contact with the journal. By the use of the present invention, however, smaller quantities of waste may be employed than heretofore considered 5 essential for efficiently lubricating the journal, as the members 6 are operated to support or hold the waste in contact with the journal. Thus it will be perceived that considerable saving may be effected by the use of 10 the present invention due to the fact that smaller quantities of waste may be used. Since, the members 6 are operated through the intermediacy of the springs 16, the latter will not only constantly exert sufficient force 15 tending to keep the waste in contact with the journal but will also absorb vibrations tending to condense the waste.

Although the waste is a comparatively homogeneous mass, due to its inherent resiliency and the fact that the fingers are spaced a relatively great distance apart, portions of the waste between the fingers will expand or sag downwardly, as shown in dotted lines in Figure 1. Thus portions of the waste will 25 always remain in contact with any oil that may be in the bottom of the box so as to maintain a thread connection between the latter and the journal. Furthermore, since portions of the waste, when the fingers are 30 in operative position also extend downwardly between the fingers of both of the members, the waste is effectually prevented from movement longitudinally and circumferentially of the journal.

35 I claim:

1. In a journal box adapted to receive a body of oil waste in a single mass in contact with the journal and the bottom of the box, means for maintaining the waste in contact 40 with the journal, said means including a pivotally mounted member provided with a plurality of fingers movable upwardly toward the journal for elevating portions of the body of waste, said fingers being arranged to permit portions of the body of waste between them to sag downwardly so as to maintain a thread connection between the bottom of the box and the journal when the fingers are 45 moved toward the latter.

50 2. In a journal box adapted to receive a body of oil waste in a single mass in contact with the journal and the bottom of the box, means for maintaining the waste in contact with the journal involving a pair of pivotally mounted members respectively provided with a plurality of spaced fingers movable upwardly toward the journal for elevating portions of the body of waste, the fingers of each member being arranged to permit portions of the body of waste between them to sag downwardly so as to maintain a thread connection between the bottom of the box and the journal when the fingers are 55 moved toward the latter.

60 3. In a journal box adapted to receive a

body of oil waste in a single mass in contact with the journal and the bottom of the box, a pair of pivotally mounted members for maintaining the waste in contact with the journal, each of said members being integrally formed with a plurality of fingers spaced longitudinally of the journal and movable toward the latter for elevating portions of the body of waste, the fingers of each member being arranged to permit portions of the body of waste between them to sag downwardly so as to maintain a thread connection between the bottom of the box and the journal when the fingers are moved toward the latter.

4. In a journal box adapted to receive a body of oil waste in a single mass in contact with the journal and the bottom of the box, means for maintaining the waste in contact with the journal, said means comprising a pair of members respectively provided with a shaft and a plurality of fingers, said shaft being pivotally mounted within the box and said fingers being movable upwardly toward the journal for elevating portions of the body of waste, the fingers of each member being spaced longitudinally of the journal a sufficient distance to permit portions of the body of waste between the fingers to sag downwardly and thereby maintain a thread connection between the bottom of the box and the journal when the fingers are moved toward the latter.

5. In a journal box adapted to receive a body of oil waste in a single mass between the journal and the bottom of the box, a pair of cooperating members for maintaining the waste in contact with the journal, said members being respectively pivotally mounted adjacent the side walls of the box, each of said side walls being rigidly provided adjacent its forward portion with a bracket and the rear wall of the box being provided with apertures respectively adjacent said side walls, said members being respectively journaled in said brackets and said apertures.

6. In a journal box adapted to receive a body of oil waste in a single mass in contact with the journal and the bottom of the box, a pair of members for maintaining the waste in contact with the journal, each of said members being provided with a plurality of curved fingers spaced longitudinally of the journal and movable toward the latter for elevating portions of the body of waste, the fingers of each member being arranged to permit portions of the body of waste between them to sag downwardly so as to maintain a thread connection between the bottom of the box and the journal when the fingers are moved toward the latter.

7. In a journal box adapted to receive oil waste, a pair of pivotally mounted members for maintaining the waste in contact with the journal, each of said members being provided

ed with a plurality of fingers, said fingers when in inoperative position being contiguous to the walls of the box and being of a shape to conform to the interior surface of 5 adjacent portions of the latter.

8. In a journal box adapted to receive oil waste, the inner surface of the lower portion of the box being curved, a pair of pivotally mounted members for maintaining the waste 10 in contact with the journal, said members being respectively disposed adjacent the side walls of the box and being provided with a plurality of fingers, the latter being curved similarly to adjacent portions of the curved 15 inner surface of the box.

9. In a journal box adapted to receive oil waste, a pair of pivotally mounted members for maintaining the waste in contact with the journal, said members being respectively 20 disposed adjacent the side walls of the box and being provided with a plurality of fingers, the interior of the box being formed with a plurality of recesses for respectively receiving said fingers.

25 10. In a journal box for receiving oil waste, a pair of pivotally mounted members for maintaining the waste in contact with the journal, and mechanism for rotating said members involving arms disposed within the box and rigidly united to the members, and means operable from the exterior of the box for actuating said arms.

35 11. In a journal box adapted to receive oil waste, a pair of pivotally mounted members for maintaining the waste in contact with the journal, said members being respectively disposed adjacent the side walls of the box and each being provided with an arm disposed within the box, and mechanisms for 40 respectively operating said members, each of said mechanisms involving rotatable means operatively connected to the arm of an adjacent member and adapted to be actuated from the outside of said box.

45 12. In a journal box adapted to receive oil waste, a pair of pivotally mounted members for maintaining the waste in contact with the journal, said members being respectively disposed adjacent the side walls of the box and each being rigidly provided with an arm disposed within the box, and mechanisms for 50 respectively operating said members, each of said mechanisms comprising rotatable means operable from the outside of the box, and flexible means operatively interposed between the rotatable means and the arm of an adjacent member.

55 13. In a journal box adapted to receive oil waste, a pair of pivotally mounted members for maintaining the waste in contact with the journal, said members being respectively disposed adjacent the side walls of the box and each being rigidly provided with an arm disposed within the box, and mechanisms for 60

respectively operating said members, each of said mechanisms comprising a member rotatably mounted in a side wall of the box and operable from the outside of the box, and a coiled spring operatively interposed 70 between the rotatable member and the adjacent arm.

75 14. In a journal box adapted to receive oil waste, a pair of pivotally mounted members for maintaining the waste in contact with the journal, said members being respectively disposed adjacent the side walls of the box and each being integrally provided with a depending arm disposed within the box, and mechanisms for respectively operating said members, each of said mechanisms involving a sleeve having threaded connection with the box and operable from the outside thereof and a coiled spring disposed within said sleeve and connected to the arm of an adjacent member.

80 15. In a journal box adapted to receive oil waste, a pair of pivotally mounted members for maintaining the waste in contact with the journal, said members being respectively disposed adjacent the side walls of the box and each being rigidly provided with a depending arm disposed within the box, and mechanisms for respectively operating said members, each of said mechanisms involving means operatively associated with an adjacent arm and mounted in a side wall of the box whereby it may be operated from the outside of said box, the latter being provided with recesses for receiving said arms.

85 In testimony whereof I affix my signature.
